UNITED STATES PATENT OFFICE.

FRANKLIN ELIJAH SMITH, OF WESTMINSTER, LONDON, ENGLAND, ASSIGNOR TO
VICKERS LIMITED, OF WESTMINSTER, LONDON, ENGLAND.

CHARGING OR REPLENISHING RECEPTACLES WITH GASES UNDER PRESSURE.

1,203,922.

Specification of Letters Patent.

Patented Nov. 7, 1916.

Application filed April 26, 1916. Serial No. 93,810.

To all whom it may concern:

Be it known that I, FRANKLIN ELIJAH SMITH, a subject of the King of Great Britain, residing at Vickers House, Broadway, 5 Westminster, in the county of London, England, have invented certain new and useful Improvements in Charging or Replenishing Receptacles with Gases Under Pressure, of which the following is a specification.

10 This invention relates to an improved method of and means for charging or replenishing receptacles with gas under pressure obtained by the combustion in a combustion chamber suitably connected to or 15 forming part of the receptacle to be charged or replenished, of a composition or substance which contains its own oxygen for supporting combustion.

The invention has particular reference to 20 the charging or replenishing of the recuperator cylinders of ordnance and the pressure reservoirs of torpedoes in circumstances in which it is inconvenient or impossible to utilize the usual plant for supplying air 25 under pressure to these cylinders and reservoirs.

Other important applications of the invention are the discharging of torpedoes from the submerged or above-water tubes 30 of warships, the blowing out of the ballast tanks of submarines, the charging of pneumatic tires, the propulsion of bombs or shells from guns and the starting or running of engines.

35 The said composition or substance is similar to the well known slow burning rocket composition.

According to the invention the gas resulting from the combustion of the composition 40 or substance (which may be solid, liquid or semi-liquid) is passed through a water or other filter which serves to prevent carbon or other undesirable impurities from being carried by the gas into the recuperator cylinder 45 or other receptacle to be charged or replenished. This filter may also serve as a cooling device for the gas but a separate cooling device may obviously be used.

In order that the said invention may be 50 clearly understood and readily carried into

effect, I will describe the same more fully with reference to the accompanying drawings, in which:—

Figures 1, 2 and 3 are respectively an elevation, a plan and a section taken approximately on the line 1—1 of Fig. 2, showing a constructional form of apparatus used in connection with the production of the pressure gas, and Fig. 4 is an elevation with parts thereof in section showing another form of the apparatus.

A represents the combustion chamber.

B represents the water filter (also serving as a cooling device) C, C, C represent carriers containing the cartridges of highly compressed combustible composition and D represents the primer for igniting these cartridges.

In the example shown by Figs. 1 to 3, the combustion chamber A and the filter B are 70 formed by the upper and lower parts respectively of a metal casing E of cylindrical shape. This casing is provided with a tube E' arranged coaxially within the filter B. Near its upper end this tube communicates 75 with the combustion chamber A and at its lower end it is normally closed by a non-return valve E'. This non-return valve may be dispensed with in which case one or more suitable openings might be formed in the 80 portion of the casing E dividing the combustion chamber A from the annular upper end of the filter B so that the pressure of the gases in the combustion chamber can be transmitted to the surface of the liquid 85 in the annular portion of the filter. The combustion chamber A is provided for four bosses a, a, a, a suitably recessed to receive the flanges c, c, c, c of the cartridge carriers C, C, C and being screw threaded externally to receive nuts c¹, c¹, c¹, c¹ which serve 90 to hold the cartridge carriers firmly in position. A suitable washer is interposed between the inner end of each cartridge carrier and the recess in each boss a.

The primer is carried in an opening D in the upper end of the tube E' which is formed with holes d, d, d (see Fig. 3) so arranged that the flash from the primer will be caused to impinge on the exposed 100

portion of the combustible composition in each cartridge.

The casing E is provided with a hole (normally closed by a plug e) by which the filter can be filled with water or other suitable liquid and is also provided with a safety valve e'. The gas is conducted from the upper portion of the filter by a bent pipe e², and a pipe leading to the recuperator or other receptacle to be charged or replenished is connected to a screw threaded hole normally closed by a plug e³. If found necessary the filter may be provided with baffle plates to prevent the gas from carrying with it any appreciable quantity of the water or other liquid in the filter.

It will be understood that although in the above described apparatus provision is made for the simultaneous ignition of four cartridges, three or fewer may be ignited, the empty carrier or carriers then serving merely as plugs to prevent escape of the gas from the combustion chamber. Although the herein described apparatus is intended to be detachably connected to the recuperator cylinder or other receptacle, it may if desired be more or less permanently fixed thereto.

In the constructional form of the apparatus shown by Fig. 4, the carriers C, C are disposed vertically within the filter B with their upper ends in communication with the combustion chamber A. Each of these carriers receives a cartridge and the portion of the casing between the carriers C, C receives the tube E' whose upper end is in communication with the combustion chamber A and whose lower end terminates close to the base of the filter B. The combustion chamber is closed by a plug E³ which is removed to enable the cartridges to be placed in their carriers C, C and is then screwed into position to close the combustion chamber. Although in Fig. 4 only two carriers are shown, four or more may be employed and arranged around the central tube E'. The apparatus comprises three combustion chambers and three tubes and sets of carriers, the other two being arranged in a similar manner to that described above and shown at the left hand part of Fig. 4. These combustion chambers are connected by passages of which one is shown at E⁴. When the cartridges are ignited by the primer the gases generated pass down the tubes E' and then ascend through the liquid in the filter B to the upper part of the filter above the liquid. The gases then pass into a chamber E⁵ at the right hand upper part of Fig. 4 and then down a tube E⁶ and up a central tube E⁷ which extends close to the lower end of the tube E⁶. In this manner any liquid carried along by the gases is trapped in a chamber E⁸ at the lower end

of the tube E⁶. At the upper end of the tube E⁷ is a spring pressed valve E⁹ which is lifted by the gases which then pass through the pipe E¹⁰ to the recuperator or other receptacle to be charged or replenished.

It will be observed that in each of the constructions shown the gases pass from the combustion chamber A through the tube E' whose lower end is situated at the lower part of the filter a substantial distance beneath the surface of the liquid. In this manner as the gases generated by the cartridges at all periods in their combustion rise from the lower end of the tube E' to the surface of the liquid, a substantially constant filtration of the gases is obtained so that the gases passing from the apparatus are of practically constant consistency at all periods during the combustion of the cartridges.

What I claim and desire to secure by Letters Patent of the United States is:—

1. Apparatus for charging or replenishing a receptacle with gases under pressure, comprising a filter, a chamber adapted to receive a composition or substance which contains its own oxygen for supporting combustion, and a conduit leading from said chamber to near the bottom of said filter so that all the gases generated by the combustion of the said composition enter the filter at one point and pass from the open end of the said conduit through the filter, thus obtaining substantially constant filtration of the gases.

2. Apparatus for charging or replenishing a receptacle with gases under pressure, comprising a liquid filter, a chamber adapted to receive a composition or substance which contains its own oxygen for supporting combustion, and a conduit leading from said chamber to near the bottom of said liquid filter so that all the gases generated by the combustion of the said composition enter the liquid filter at one point and pass from the open end of said conduit through the liquid filter, thus obtaining substantially constant filtration of the gases.

3. Apparatus for charging or replenishing a receptacle with gases under pressure, comprising a filtering and cooling device, a chamber adapted to receive a composition or substance which contains its own oxygen for supporting combustion, and a conduit leading from said chamber through said device to near the bottom of said device so that all the gases generated by the combustion of the said composition enter the device at one point and pass from the open end of said conduit through the said device, thus cooling the gases and obtaining substantially constant filtration of said gases.

4. Apparatus for charging or replenish-

ing a receptacle with gases under pressure, comprising a liquid filtering and cooling device, a chamber adapted to receive a composition or substance which contains its own oxygen for supporting combustion, and a conduit leading from said chamber through said device to near the bottom of said device so that all the gases generated by the com-

bustion of the said composition enter the device at one point and pass from the open end of said conduit through the said device, thus cooling the gases and obtaining substantially constant filtration of said gases.

In testimony whereof, I hereunto affix my signature.

FRANKLIN ELIJAH SMITH.
